UNITED STATES PATENT OFFICE

93,280

DESIGN FOR A HOPPER FOR STOKERS

Robert W. McFadden, Orrville, Ohio, assignor to
The Will-Eurt Co., Orrville, Ohio, a corporation
of Ohio

Application June 28, 1934, Serial No. 52,365

Term of patent 7 years

To all whom it may concern:

Be it known that I, ROBERT W. McFADDEN, a citizen of the United States of America, residing at Orrville, in the county of Wayne, in the State of Ohio, have invented a new, original, and ornamental Design for Hoppers for Stokers, of which the following is a specification, reference being had to the accompanying drawing, forming part thereof.

The figure is a perspective view of a hopper for stokers showing my new design.

I claim:

The ornamental design for a hopper for stokers, as shown.

ROBERT W. McFADDEN.
